UNITED STATES PATENT OFFICE.

ROBERT CRAWFORD LYNESS, OF SUNDERLAND, ENGLAND.

CONTACT-FINGER FOR ELECTRICAL CONTROLLERS AND SWITCHES.

977,460.

Specification of Letters Patent. Patented Dec. 6, 1910.

Application filed June 27, 1910. Serial No. 569,157.

To all whom it may concern:

Be it known that I, ROBERT CRAWFORD LYNESS, citizen of Great Britain, residing at 14 Waterloo Place, Sunderland, in England, 5 have invented new and useful Improvements in Contact-Fingers for Electrical Controllers and Switches, of which the following is a specification.

The object of my invention is to provide 10 a contact finger as required for electrical controllers and switches, so that such finger can if desired be easily attached to the contact base of the controller, and furthermore that the tip of such finger, which may have 15 one or more wings, as hereinafter described, can be easily attached to such finger when owing to wear and tear or other circumstances, such tip requires replacing or reversing.

20 To attain my object I provide a metallic strip which I call the finger, also a detachable tip for same. The tip end of this finger is formed by folding back the strip in such a way as to provide a recess of a desired 25 shape. This recess is as far as its outer surface is concerned of a similar design to, but slightly larger than, the internal surface of the recess in the finger tip mentioned hereafter, which has to be attached thereto.

30 The tip, which is shown in Figure 2 of the drawings, may be formed of one projection or wing, as shown by dotted line "D," or may have two side projections or wings, as shown by dotted line "C" Fig. 2, and the 35 method of attachment is simply by pressing the parts of the strip forming the shaped recess together, and allowing the tip to slide into the desired position. If desired, I provide the lips of the tip with one or more 40 grooves, and on the finger I provide suitable projections corresponding with such grooves so that the attachment is made the more secure. At the contact base end, or the end of the finger which has to be attached to the contact base of the controller, I also fold the metallic strip, forming a recess having the outer surface to correspond 45 to, but slightly larger than the inner surface of a recess in the bracket mentioned hereafter.

50 I provide a bracket with a recess the inner surface of which corresponds to, but is slightly smaller than, the outer surface of the recess formed at the base end of the 55 finger, so that such finger can be attached to such bracket in the same way as the finger

is attached to the tip. The bracket is attached by means of screws or other methods to the base of the controller. Similar grooves and projections to those on the tip 60 and tip end of the finger may be formed on this bracket and base end of the finger respectively.

If it is desired to attach the finger to the existing type of controllers, then the metallic strip is not folded back at the base 65 end, but it is provided with the existing means of attachment, namely by screws or other similar methods.

To further illustrate my invention, I furnish the accompanying drawings:—

Fig. 1, represents top or sectional view of a metallic finger having the base end plain for ordinary attachment to controller, "A" is the formed recess to receive the tip shown 75 on Fig. 2, "B" is an adjusting screw with lock nut, "E" shows the projections on strip, which correspond to recesses "F" on Fig. 2.

Fig. 2, shows a top view of the metallic 80 tip which slides over the recess at the tip end of Fig. 1 when the wing of the finger strip is compressed. The shape of this tip may be varied as for instance according to the dotted lines "C" or "D," "F" shows 85 the small recesses in the metallic tip which correspond with the projections "E" in Fig. 1.

Fig. 3, shows a front view of metallic finger tip and entrance to recesses therein. 90

Fig. 4, is a front view of Fig. 1.

Fig. 5, shows a finger having a formed recess at each end, the outer end showing a tip attached thereto, while the inner or base end is arranged to fit in to the bracket shown of 95 Fig. 7.

Fig. 6, is a front view of Fig. 5.

Fig. 7, shows a section of a bracket which is attached to the controller base, and is provided with a recess corresponding to the external surface of the recess at the base end of the finger shown on Fig. 5.

Fig. 8, is a front view of Fig. 7.

Having now particularly described and ascertained the nature of my said invention, 105 and in what manner the same is to be performed, I declare that what I claim is:—

1. In combination, a contact finger comprising a metal strip having one of its ends bent back to form a loop and a contact tip 110 having a recess adapted to embrace said loop.

2. In combination, a contact finger com-

prising a resilient metal strip having one of its ends bent back to form a loop and a contact tip having a recess adapted to embrace said loop, whereby it is retained in position by the resiliency of the metal forming the loop.

3. In combination, a contact finger comprising a metal strip having one of its ends bent back to form a loop and a contact tip having a recess adapted to embrace said loop, said recess being of the same configuration as said loop but being of smaller dimensions, whereby when said tip is in position upon said finger the portions of the strip forming the loop will be pressed inward from their normal position.

4. In combination, a contact finger comprising a metal strip having one of its ends bent back to form a loop, said loop being provided with an outwardly extending pro-

jection and a contact tip having a recess adapted to embrace said loop, the wall of said recess being provided with a depression adapted to be engaged by said projection.

5. In combination, a contact finger comprising a resilient metal strip having one of its ends bent back to form a loop and a contact tip having a recess adapted to embrace said loop, whereby said tip will be retained in position by the resiliency of the metal forming the loop, the other end of said contact finger being bent back to form a resilient loop for attaching the finger to a support.

In testimony whereof I have signed my name to this specification in the presence of two subscribing witnesses.

ROBERT CRAWFORD LYNNESS.
